Inventor:
Harry N. Radis,
By Bertha L. McGregor
Atty.

UNITED STATES PATENT OFFICE.

HARRY N. RADIS, OF CHICAGO, ILLINOIS.

NECKTIE HOLDER.

Application filed May 12, 1928. Serial No. 277,201.

This invention relates to neck tie holders. The object is to produce a convenient tie holder or foundation forming device over which a neck tie may be tied, by means of which the tie need not be untied when it is desired to remove the same by the wearer.

Another object is to produce a device which will enable the wearer to readily connect the free end of the tie to the tied or knotted portion when donning the tie.

Another object is to produce a device of the character described from a single piece of relatively stiff wire.

In the drawings:

15 Figure 1 is a perspective view of a tie holder embodying my invention, as viewed from the rear and slightly from the right side.

Figure 2 is a rear elevation.

20 Figure 3 shows the holder of Figure 2 with the tie, broken away, in its first position.

Figure 4 is similar to Figure 3, showing the second position of the tie.

Figure 5 is similar to Figure 3, showing the third position of the tie.

25 Figure 6 is similar to Figure 3, showing the fourth position of the tie.

Figure 7 is similar to Figure 3, showing the fifth position of the tie.

Figure 8 is a rear view of the holder with 30 the tie in knotted position thereon.

Figure 9 is a front view of the tie shown in Figure 8.

Figure 10 is a rear view of the tie showing 35 how the free end thereof is engaged by the holder.

In that embodiment of my invention shown in the drawings the tie holder is formed by bending a piece of relatively stiff wire to form a vertically disposed bar 11, a short 40 rearwardly extending part 12, another upright member 13 parallel with the bar 11 and somewhat longer than the latter, a twisted portion 14 from which extends a lateral, angular portion 15. The device is being described by treating that portion which will 45 be nearest the body of the wearer when in position as the rear part and the parts thus far described from what may be termed the left hand side of the holder.

50 Continuing, the wire extends across the front of the device from said angular portion 15 in a slightly upward direction as indicated at 16 and laterally to a greater extent than the part 15. At 17 the wire is again 55 bent rearwardly and then downwardly as in-

dicated at 18 toward the lower end of the vertical bar 13, then forwardly, 19, parallel with and closely adjacent the part 12, then upwardly as indicated at 20 parallel with and closely adjacent the side of the upright bar 11 60 at the front of the device; then bent slightly sidewise as indicated at 21, and then doubling back at 22, 23 and 24, parallel with and closely alongside of the parts 21, 20 and 19, respectively.

65 Those parts of the wire indicated at 16 to 24, inclusive, may be termed the right side of the holder, although it will be understood that the device is integral.

In using the holder, it is held as it is shown 70 in Figure 3, looking at the rear or part which will be nearest the wearer when in use. The neck tie is then passed between the upright bars 11 and 13, the end B being in rear of the wire 18 so that said part B may be folded 75 back upon the part A as shown in Figure 4. In this position the tie is looped only upon the upright member 13 of the left hand side of the holder.

The part A is then brought forwardly and 80 in front of the vertical supports 11, 20 and 23, the free end of the part A being passed slightly rearwardly between the bars 16 and 18 and upwardly so as to rest in the curve 17 of the wires 16 and 18, as shown in Figure 5. 85 The free end of the part A will have been drawn outwardly so as to leave the tie in smooth position across the front of the holder. This curved part 17 between the wires 16 and 18 affords a support for that part A of the 90 tie which is the untied portion intended to surround the neck of the wearer and finally to be engaged by the holder after the part B has been properly tied or knotted thereon.

The part B is now also brought forwardly 95 and across the front of the device outwardly of the part A of the tie (this portion, which will form the tie knot, being indicated at C), then rearwardly and downwardly as shown in Figure 6, then upwardly in rear of 100 the inclined bar 18, then over the top of the angular part 15 and wire 16, and downwardly between the parts A and C of the tie overlying the front of the holder.

The free end of the part B will then be directed downwardly and may be pulled so that the knot C will assume its proper form.

The free end of the tie A is now ready to be placed around the neck of the wearer and will be engaged and held in desired position 110

between and by the proximate arms 12 and 19 of the left and right sides, respectively, of the holder.

To remove the tie, it is only necessary to draw the engaged portion A rearwardly out of engagement with said arms 12 and 19, without untying the knot C or marring the perfection thereof.

While the particular form of device shown and described is my preferred form of holder, which has been found very efficient, obviously the device may be simplified and modified without departing from the scope of my invention, the important features of which are to provide a proper support for the tie knot, in combination with a pair of spring arms such as the parts 12 and 19 or their equivalent, for engaging the untied portion of the neck tie.

20 I claim as my invention:

1. A neck tie holder comprising a single piece of relatively stiff wire bent to form a cross bar and downwardly extending side portions terminating in a pair of spring arms 25 extending at an angle to said side portions and in frictional contact with each other.

2. A neck tie holder made from a piece of relatively stiff wire bent to form a forwardly located upright bar, a short rearwardly extending arm, another upright bar located 30 rearwardly of said first bar, an angular side portion, a front cross bar, a curved and downwardly inclined portion extending to said rearwardly extending arm, and a forwardly directed arm in frictional engagement with 35 the latter.

3. A neck tie holder made from a piece of relatively stiff wire bent to form a forwardly located upright bar, a short rearwardly extending arm, another upright bar located 40 rearwardly of said first bar, an angular side portion, a front cross bar, a curved and downwardly inclined portion extending to said rearwardly extending arm, a forwardly directed arm in frictional engagement with the 45 latter, and another upright member adjacent said first mentioned upright bar.

In testimony that I claim the foregoing as my invention I affix my signature, this 10th day of May, 1928.

HARRY N. RADIS.
